REFILLABLE BROOM, BRUSH, AND THE LIKE

Gaetano Pignato, Brooklyn, N. Y.

Application July 20, 1950, Serial No. 174,837

2 Claims. (Cl. 15—172)

1

This invention relates to new and useful improvements in sweeping implements, such as brooms; and, more particularly, the aim is to provide a novel and valuable implement characterized by an improved combination of handle, broom or brush head, and refill for the latter.

Said refill may comprise, in the case of a broom, a bundle of broom corn or the like, bundled in any suitable way, as by the stitching long familiar in the art of bundling broom corn and the like incidental to the making of an ordinary broom with the broom corn or the like permanently attached to the broom handle. In the case of the present invention, however, the placement of said stitching or equivalent, as wire ties, or any other means used for bundling the broom corn or equivalents, is intermediate the ends of the bundle, and the bristles of the bundle have their opposite ends at the opposite ends of the bundle, thereby to provide a reversible or double-use refill.

Also provided by the present invention is an exceptionally simple and inexpensive structure, partly included in the refill and partly incorporated in the broom or brush head, so constructed that a broom corn or equivalent bundle already in the broom or brush head may be quickly and easily removed therefrom for discard or reversal, that a partially worn bundle after removal and reversal, or a new or replacement bundle, may be quickly and easily mounted in the broom or brush head, and that, nevertheless, any bundle when mounted as intended in the said head is dependably securely held at its mounting during and between uses of the broom or brush as such.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a side elevation of one of the many possible now favored embodiments of the invention; this shown, for example, as a sweeping broom.

Fig. 2 is an end elevation thereof.

Fig. 3 is an enlarged vertical section, taken on the line 3—3 of Fig. 2; with the refill merely indicated, in dot and dash, in two possible placements of said refill in the broom head.

Fig. 4 shows said refill in top perspective, detached.

2

Fig. 5 is a horizontal section, taken on the line 5—5 of Fig. 4.

Fig. 6 is a further enlarged detail section, this as though taken on the line 6—6 of Fig. 5, but illustrating a modification.

Fig. 7 is a side elevation, partially broken away and partially in section, of another of the many possible now favored embodiments of the invention; this shown, for example, as a paint brush or the like.

Fig. 8 is an end elevation thereof.

Fig. 9 is a view similar to Fig. 7, but illustrating a modification.

Fig. 10 is a perspective view of a core portion 15 which may be used for being inbuilt in a refill pursuant to the invention; this core section being also seen in Fig. 9.

Fig. 11 is a perspective view of the handle of Figs. 7—9, detached.

Fig. 12 is a section taken on the line 12—12 of Fig. 7.

Fig. 13 is a section taken on the line 13—13 of Fig. 7.

Fig. 14 is a bottom plan view of Fig. 7.

25 Referring now to the drawing more in detail, and first to Figs. 1—5, the broom here shown in illustration of the principles of the invention comprises a handle 10, a broom head which as a whole is designated 11, and a reversible or double-use refill 12.

As will be understood, the invention is not to be limited to material or materials used. Thus the handle 10 may be made of wood, metal, a plastic or any other desired material; and this 35 comment applies also so far as are concerned the broom head 11, the material or materials of which it is made, the manner of attachment of the handle to the broom head, and whether or not the handle is stationary, that is, fixed 40 relative to the broom head, or detachably to be secured to the latter. The invention, too, is broader than the means used to attach or connect the handle to the broom head, or any portion of the broom head to any other portion thereof.

45 Also, in regard to the refill, the invention is not to be limited to the kind or kinds of bristles used, as broom corn or otherwise, fibrous or not, and natural or artificial, as nylon or some other plastic, or if natural whether vegetable or animal; nor to the shortness or length of the bristles or their relative fineness or thickness. In connection with the allusion to animal bristles just made, it is further to be preliminarily understood that the principles of the

invention may be applied to paint brushes, or the like, as well as to brooms and sweeps.

In the present case, and by way of example only, the handle 10 may be assumed to be merely a round wooden rod of appropriate length and of suitable diameter; and the broom head 11 may be assumed to be made of thin sheet metal which may be given a desired elastic set, thereby to have the same effectively carry a pair of snap lips to be referred to in a moment.

As said broom head 11 is illustrated it includes a main shell 14 shaped to provide a compartment or socket 14' closed over at its top and closed in all around its four sides but open at its bottom.

Said compartment or socket 14' is elongate in horizontal section, so that two of its side walls are of considerably greater width than the two other, or end, walls alternating around the socket with said wider walls. These wider walls, which are exactly alike and which may be for convenience called the front and back walls, are respectively designated 15 and 16; and they have lower portions extended below the bottoms 17 and 18 of the end walls, which end walls are also exactly alike.

Said bottom portions of said walls 15 and 16 are substantially frusto-triangular, that is, each of said bottom portions, respectively designated 19 and 20, is bounded along opposite sides by downwardly inclined converging edges; these edges marked 21 and 22 (Fig. 3) in the case of the back wall 16.

Said wall portions 19 and 20 constitute fairly stiff leaf-spring instrumentalities each carrying at its bottom one of the aforesaid pair of snap lips. Since, as already stated, the walls 15 and 16 are exactly alike, said snap lips are exactly alike. Each of said lips, both designated 23, is in the form of a substantially rectangular horizontally elongate panel-like downward extension; and each of said extensions is formed to carry longitudinally thereof a groove 24 the concavity of which faces the concavity of the corresponding groove in the other of said extensions.

The broom head 11 is shown as also including an auxiliary shell incorporating a basal shawl-like portion 25 and an upstanding neck portion 26; said portion 25 for straddling and closely embracing the top and upper side wall portions of the mainshell 14, and there being suitably firmly attached, as by brazing, soldering, welding or in any other suitable and convenient way, and said neck portion 26 for having inserted therein as illustrated an end of the handle 10. In the present case, a rivet 27 is shown as the means for obtaining a suitable permanent securing of the handle in said neck portion.

The refill 12 is illustrated as made of broom corn as in the ordinary household broom, but with the broom corn bundled, although so bundled by lines of stitching (28, Fig. 4) into a tightly compacted mass at the zone of said stitching as in the case of the ordinary broom, to establish said zone at a new location; in other words, while said lines of stitching extend across the bundle, as is conventional, they so extend intermediate the ends of the bristles, thereby to provide, in one direction beyond said zone and also in the opposite direction beyond said zone, a different broom corn sweeper means. In Fig. 4, one of said sweeper means is designated 29, and the other of said sweeper means is designated 30.

Suitably clamped on the refill 12, and running

all around the latter at said zone, is a structure 31 to provide a bead element at each side of the refill. As herein shown, the structure 31 is merely a length of wire of generally circular cross-section crimped tightly around the refill at the zone where the stitchings 28 are applied; the plane of the structure 31 when thus crimped being parallel to the planes of the bristles' ends at each end of the refill, and the shape of said structure when so crimped being such as to conform to the shape of said zone cross-sectionally of the refill as shown in Fig. 5.

Said zone cross-section, as will be understood, is such, relative to the area and shape of the bottom opening of the compartment or socket 14', and relative to the natural spread of the broom corn bristles in both directions away from said zone, that when the refill 12 is mounted in the broom head 11 in any one of a plurality of different dispositions therein, the structure 31 of the refill will lie properly between the pair of snap lips 23, one of the two sweeper means 29 and 30 of the refill will be confined in the compartment or socket 14 and the other of said sweeper means will be projected below said lips for constituting the then operative sweeper means, and the grooves 24 will be snap-locked into engagement with the portions of the structure 31 constituting the already mentioned bead elements at opposite sides of the refill thereby dependably securely to hold the refill at its selected mounting relative to the broom head during and between uses of the broom as such.

In manufacturing the refill, the two oppositely extending sweeper means may be of the same length, that is, the structure 31 or equivalent may be applied centrally of the length of the refill; or said two sweeper means may be made of different lengths, for differential sweeper action as desired at different times and under different cleaning conditions, by placing the structure 31 or equivalent at a point closer to one end of the refill than to the other.

An arrangement like that last referred to is, by way of example, illustrated herein; it being noted that the sweeper means 30 is shown as somewhat longer than the sweeper means 29. In Figs. 1 and 2, the sweeper means 29 is shown as the one projected below the broom head for constituting the then operative sweeper means; while in Fig. 3, the dot and dash depictions 29' and 30' indicate the working ends of, respectively, the sweeper means 29 and 30 with the latter disposed as in Figs. 1 and 2, and the dot and dash lines 29'' and 30'' indicate the planes of the working ends of, respectively, the sweeper means 29 and 30 when the refill 12 is so disposed in the broom head 11 that it is the longer sweeper means 30 which is projected below the broom head.

Referring to the modification illustrated in Fig. 6, here a structure 31^a corresponding to the structure 31 is shown which, for being shaped and crimped as has been explained in connection with the structure 31, is made of a length of wire of substantially generally round cross-section and which also is longitudinally corrugated as shown, with these corrugations preferably very small and close together so as not appreciably to weaken said wire or interfere with said shaping and crimping, and with said corrugations also preferably so contoured that the crests of certain of them will be forced to an exceedingly tight and immovable yet non-damaging grip on

the refill at the zone where the structure 31^a is applied.

While the embodiment of the invention as shown in Figs. 1-6 and as above described is illustrative of an application of the principles of the invention to a sweeping broom, and the embodiment next to be described as shown in Figs. 7-14 is illustrative of the principles of the invention as applied to a paint brush, it is to be understood that any or all of the improvements typified in Figs. 1-6 may be applied to a paint brush and that any or all of the improvements typified in Figs. 7-14 may be applied to a broom.

Referring to Figs. 7, 8 and 11-14, a shell 32 is provided which differs from the shell 14 in several ways. The shell 32 has rectangular front and rear as well as end walls, with the bottoms of all these walls in the same plane; that is, elements corresponding to the elements 19, 20, 23 and 24 are omitted. The said shell 32 at the center of its roof wall has an aperture for endwise insertion therethrough of the handle, said handle designated 33; and which aperture may be surrounded by a neck 34 as shown.

The lower end of the handle 33 has an external thread 35. Said thread is for being screwed into an internally threaded socket 36 extended all the way through the thickness of a core section 37 of metal, wood, plastic or any other suitable material; said socket being placed at the center of said core section, and the latter being doubly beveled at its opposite ends as shown at 38 in Fig. 7. The end walls of the shell 32 being outwardly flared as indicated at 39 in Figs. 7 and 8, and the handle 33 being shouldered as shown at 33', said core section may be fitted in the bottom of the shell 32, either as shown in Figs. 7 and 8 or upside down, in such manner that after passage of the handle 33 through the neck 34 and screwing of the threaded end 35 of the handle into the socket 36, all three of the handle, the shell 32 and said core section are immovably locked together.

Said core section 37 is shown as the carrier of two groups 40 and 41 of brush bristles, said bristles being anchored in the core section, as by having the bristles arranged in tufts with such tufts embedded in the core section material, or attached in any suitable manner to the core section. Thus, a double-use refill 37-40-41 is provided pursuant to the invention, readily reversible in the brush head afforded by the shell 32, for use of either selected one of the bristle groups 40 and 41 as the working bristle end of the implement and with the other of said groups housed in the shell 32.

Since the outer ends of the bristles of each of the groups 40 and 41 will tend to close in toward their companion bristles in the same group, at their end portions remote from the core section 37, the points of securement of the different bristles of a group 40 or 41 thereof to said core section may be so spaced relative to the threaded socket 36 that the group of bristles to be housed in the shell 32 may be temporarily forced to slight abnormal separation to provide a tunnel through which the handle 33 may be advanced for being screwed into the socket 36, yet so that the other group of bristles will have a satisfactorily even spread at their ends remote from the said core section.

Referring to the modification of Figs. 9 and 10, in which modification, for a reason to become plain in a moment, the handle 33 may be of uniform cross-section from its outer end down to

the beginning of the thread 35, a shell 42 is shown which is exactly like the shell 14, so far as are concerned inclusion of elements exactly like the elements 19, 20, 23 and 24 of said shell 14. At its top, however, the shell 42 is shown as like the shell 32, the shell 42 having an aperture for the endwise insertion therethrough of the handle 33, said aperture in the shell 42 being shown as surrounded by a neck 43 corresponding to the neck 34.

The double-use refill as here used has a core section 44, also made of metal, wood, plastic or any other suitable material, and having along its opposite sides bead elements 45, 45 corresponding to the bead elements hereinabove described as provided by the structure 31 of Figs. 1-5.

Said core section 44 has an internally threaded clearthrough socket 46 corresponding to the socket 36; and thus, with the thread 35 of the handle tightened in said socket, to dispose either one of the group of bristles 47 and 48 secured to and projected from the opposite faces of the core section 44 so that that group projects beyond the brush head provided by the shell 42 and the other group is housed in said shell 42, the spring lips at the bottoms of the wider sides of said shell and carrying oppositely facing grooves corresponding to the grooves 24 coact with the bead elements 45, 45 dependably securely to lock the refill in the brush head.

The elements shown at 49 in Fig. 10 may represent well-like depressions in the seen face of the core section 44, with like depressions in the hidden face of said core section, in each of which depressions at one face of the core section tufts of the bristles of the group 47 may be suitably secured, and in each of which depressions at the opposite face of the core section tufts of the bristles of the group 48 may be suitably secured. Or said elements 49 may represent clear-through apertures, for the securement therein, as by suitable adhesive or manner of embedment, of the mid portions of long bristle tufts, thereby to have the end portions of said tufts participate in the establishment of both the groups 47 and 48.

While I have illustrated and described the preferred embodiments of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:

1. In an implement of the type including an elongate handle and a working means offset from an end of the handle and of the type wherein said working means is of the kind comprising a multiplicity of elongate flexible elements gathered or bundled together as in a broom or in a paint brush or the like, the combination, with said elongate handle, of a hollow head, means for connecting said head to the handle, a reversible double-use refill, said refill incorporating two oppositely extended groups of said elongate elements, said refill being shaped and dimensioned for being mounted on the implement by partial insertion of the refill into the hollow head for then projecting beyond said head one only of said groups, and means partially carried by said refill for detachably thus mounting the refill with either of said groups as the one so projected beyond said head, said refill having a portion

between said groups from opposite sides of which said groups are extended, said portion carrying the part of the last-named means partially carried by said refill, said part of said means including an internally threaded aperture through said portion, and said handle having an externally threaded end for being screwed into said aperture through either end thereof between said flexible elements, said part of said means further including a plurality of spaced projections on said portion of the refill.

2. In an implement of the type including an elongate handle and a working means offset from an end of the handle and of the type wherein said working means is of the kind comprising a multiplicity of elongate flexible elements gathered or bundled together as in a broom or in a paint brush or the like, the combination, with said elongate handle, of a hollow head, means for connecting said head to the handle, a reversible double-use refill, said refill incorporating two oppositely extended groups of said elongate elements, said refill being shaped and dimensioned for being mounted on the implement by partial insertion of the refill into the hollow head for then projecting beyond said head one only of said groups, and means partially carried by said refill for detachably thus mounting the refill with

either of said groups as the one so projected beyond said head, said refill having a portion between said groups from opposite sides of which said groups are extended, said portion carrying the part of the last-named means partially carried by said refill, said part of said means including an internally threaded aperture through said portion, and said handle having an externally threaded end for being screwed into said aperture through either end thereof between said flexible elements, said part of said means further including a plurality of spaced projections on said portion of the refill, said last-named means further including a pair of snap lips elastically carried by the hollow head and shaped and arranged for elastically seizing between them said projections.
